SELF CLEANING ATOMIZER

Walter Macdonald, North Providence, R. I.

Application June 26, 1936, Serial No. 87,370

20 Claims. (Cl. 299—59)

My invention relates to atomizers of the self cleaning type for converting a fluid from a liquid to a vapor, whether accomplished by impact or turbulence or both.

5 Certain important objects of this invention are to provide thoroughly effective automatic means for cleaning the discharge orifice or passages of an atomizer nozzle; to completely clean a passage for liquid through the jet, and through an annular passage for air between the jet and nozzle each time the atomizer operates; to so dispose the parts as to create in their natural operation an auxiliary pressure through the nozzle in excess of the initial pressure afforded by the compressed air, whereby the discharge of the liquid is accelerated when the cleaning members are withdrawn; and to effect all the above results in a device of maximum compactness, economic in construction, and containing a single nozzle only.

10 Further objects are to facilitate the assemblage of the constituent parts of the atomizer; to insure the travel of the liquid throughout the length of the casing in a non-angular course; to control and vary the volume of the spray; to prevent clogging accumulations around the jet, and to shield the latter against injury.

15 With the above and other objects and advantages in view, which will fully appear and be adverted to in the following description, my invention consists in such parts and in such combinations of parts as fall within the scope of the appended claims.

20 In the accompanying drawings which are a part of this specification, and in which is shown a preferred embodiment of my invention,

25 Figure 1 is a side elevation of my self cleaning atomizer.

Figure 2, a vertical medial section of the same in closed position,

30 Figure 3, a similar section of the same in open position,

Figure 4, a section taken on line 4—4 of Figure 3,

Figure 5, an enlarged fragment of the section shown in Figure 1, and

35 Figures 6 and 7, perspective views of the tubular cleaning member and jet respectively.

The invention will be described in connection with the specific embodiment shown, and it will be understood that the invention is not to be limited by such specific showing except for such limitations as the claims impart.

40 My atomizer includes a casing 15 comprising a tubular side 16 whose reduced front and rear margins are threaded, as at 17 and 18, to engage

flanged nuts 21 and 22 respectively whose flanged portions 23 and 24 engage front and rear end plates 25 and 26 respectively.

The front end plate 25 has a central opening 27 provided with a thread 28. A nozzle 29 includes a shank or body portion 30 and a terminal flange 31. The former is provided with a central orifice 32 from which a forwardly directed outwardly flaring cavity 33 extends to the flange. The forward portion of the orifice has a cylindrical wall 35, while its rear portion has an annular rearwardly directed tapering recess 36 extending from the orifice to the end face 37 of the shank.

An axially disposed tubular pipe 42, having an annular shoulder 44 near its rear end, is threaded, as at 45, in a central orifice 47 in the end plate 26 of the casing. An extension 48 of this shoulder abuts against the rear face of the plate. Adjacent the extension a projecting portion 50 of the holder is provided with an external thread 51 adapted to engage a supply pipe for liquid. Intermediate its length the pipe 42 is provided with longitudinally disposed slots 52 diametrically opposite each other.

A tubular liquid jet 54 carried by the pipe 42 includes a shank portion 55 having threaded engagement, as at 56, with the forward end of the pipe, an inwardly directed intermediate external shoulder portion 57, and a forwardly directed stem portion 58. An axial passage 59 through the jet comprises a rear portion 60 of ample diameter in the shank, a forward portion 61 of less diameter in the stem, and an intermediate tapering portion 62 in the head, the last mentioned portion forming a conical shoulder or valve seat. The stem portion 58 extends centrally within the orifice 32 of the nozzle 29 thus forming a central discharge passage 63 for the liquid, and a resultant annular opening or passage 64 around the periphery of the stem for egress of compressed air.

A cleaning rod 65 for the jet 54 has an enlarged body 66 movable in the portion 60 of the axial passage of the jet; a tip 67 slidable in the portion 61 of the passage in the stem; and an intermediate tapered shoulder 68 adapted to contact with the valve seat 62. The body of the member 65 is fixed by a rivet 69 or otherwise at its rear end to the center of an elongated pressure responsive element or plate 70 extending transversely of the jet holder 42 with its ends loosely projecting through the slots 52. As the width of the element is less than the internal diameter of the holder 42 there are resultant passages 71 for the liquid

at each side of the element. A compression spring 72 surrounding the holder has its ends engaging the shoulder 44 and the element 70, and normally maintains the cleaning member in advanced position.

A tubular cleaning member or sleeve 74 for the air passage 64 includes a cylindrical skirt or body 75 loosely surrounding the jet 54, an intermediate inwardly directed shoulder 76 longitudinally spaced from the shoulder portion 57 of the jet holder when the operating parts are in normal closed position, and a forwardly projecting sleeve 78 integral with the shoulder slidably engaging the tip or stem 58 of the jet and the cylindrical wall 35 of the nozzle in the annular passage 64 which it normally closes. Integral with the open inner end of the skirt 75 is an external annular shoulder 79 which affords an increased bearing area upon the element 70 against which it normally abuts. The shoulder 76 of the skirt normally contacts with the nozzle 29. A packing ring 81 engages the forward face of the shoulder 79, and a like ring 82 is interposed between the jet shoulder 57 and the cleaning member shoulder 76.

The jet 54 and cleaning member 74 are disposed concentrically within a compressible resilient housing 84. The latter includes an annular base 85 clamped in rigid engagement with the rear end plate 26 by the cooperation of the nut 22 with the casing side 16, and is fixed to the rear end of the resilient collapsible body 87, preferably of metal, to whose forward end is fixed a head 89 normally abutting against the nozzle 29 and provided with a central opening 90 into which extends the skirt of the cleaning member 74. A longitudinal rearwardly directed extension 91, integral with the head 89 and spaced from the opening 90, contacts with the front face of the element 70, while the inner margin of the head is in horizontal alignment with the packing ring shoulder 79 of the member 74.

An inlet pipe fitting 92 has one end threaded in an inlet opening 93 in the side 16 of the casing, and has an external thread 94 adapted to engage a pipe leading from the source of supply of compressed air for introduction into the single partitionless chamber 95 enclosed by the casing 15.

When the device is in normal closed or non-discharging position the operating parts are disposed as hereinabove described, and as illustrated in Figure 2, wherein the passage 61 of the stem portion 58 of the jet 54 for the liquid is occupied by the advanced cleaning member 65; and the annular air discharge passage 64 between the nozzle and the stem of the jet is occupied by the cleaning member 74. The cleaning members are positively maintained in their advanced closed positions by the pressure exerted by the expansive action of the spring 72 upon the pressure responsive element 70.

The liquid is introduced into the liquid conducting pipe or jet holder 42, which defines the axis of the casing a major portion of the length of the latter, in any convenient manner from any convenient source of supply, while air under pressure is supplied through the inlet opening 92 of the casing, and acts upon the exterior of the head 89 to compress the housing 84. As the head recedes its inner margin engages the packing ring 81 upon the shoulder 79 and withdraws the cleaning member 74 from the air passage 64, and simultaneously, through the extension 91 and the element 70, withdraws the

cleaning member 65 from the passage 61 for the liquid, and moves the shoulder portion 68 of said member from the valve seat 62, thus permitting the free discharge of the air and liquid through their respective passages 64 and 61.

When the air pressure ceases the head 89 of the housing is moved to its original advanced position under the influence of the resilient body 87, thereby releasing the cleaning member 74, and the element 70 to which the cleaning member 65 is attached, whereupon the spring 72 advances the element 70, which in turn contacts with and advances the member 74, and forwardly impels the member 65, to their original advanced occluding positions. Thus the repeated advance of the sleeve 78 of the member 74 cleans the exterior of the jet stem 58 and the cylindrical wall 35 of the nozzle orifice, and the member 65 cleans the interior of the jet stem.

The element 70 has lateral and radial play in the slots 52 in which it slides. Therefore during the above described advance of the cleaning member 65 its tip 67 is insured entrance into the passage 61 of the stem by contact of the free end of the tip with the valve seat 62 of the jet 54. This automatic or self centering feature dispenses with the necessity of delicate and difficult pre-alignment of the cleaning wire or member or machining the parts; also enable the employment of a short and space saving member; and avoids the employment of an auxiliary clamping plate.

When the air under pressure is introduced into the chamber of the atomizer the housing is compressed thereby while the air is also discharging through the air passage 64 of the nozzle thus creating a vacuum in the jet 54 and, because of the slots 52, the vacuum extends to the interior of the housing. The negative pressure or vacuum upon the inside combined with the positive pressure upon the exterior of the housing, set in unison to create a total operating pressure upon the latter greater than the initial pressure of the compressed air, and induces the liquid to accelerate its advance to the point of atomization.

The disposition of the liquid conducting pipe 42 axially of the casing, and within and concentric with the housing member 84, and the concentric and telescoping relation of the clearing member 65, with relation to the jet 54, and the cleaning member 74 with relation to both the jet 54 and the portion 91 of the housing head 89, contribute to the compact character of the entire structure, and renders unnecessary transverse partitions as well as liquid and air units angularly disposed with relation to each other. The mutually concentric relation of the parts combined with the accessibility thereto by reason of the detachability of all the threaded sections constituting the casing 15 of the atomizer, facilitate the assemblage of the entire structure.

The axial adjustability of the nozzle relatively to the jet furnishes means for determining the point of maximum efficiency of the spray. The inward or rearward movement of the nozzle determines the magnitude of the spray cone. This movement also decreases the amount of moisture vaporized in direct relation to the amount of compressed air employed. This is economically important as compressed air is very expensive.

I claim:

1. In an atomizer of the type set forth, a casing adapted to receive air under pressure, a liquid conducting pipe mounted in the casing, a

- nozzle in the casing provided with an orifice for the discharge of air and liquid, an element slideable along the pipe adapted to be moved by the air pressure in a direction away from the nozzle, 5 a jet upon the pipe extending into and in spaced relation to the orifice, a cleaning rod attached to said element constructed and arranged to be moved thereby in a direction toward the nozzle and to close the jet, a cleaning sleeve in the path of said element axially slideable upon the jet and constructed and arranged to be moved by said element in a forward direction to close the portion of the orifice exterior of the jet, and resilient means arranged to oppose the 10 movement of said element occasioned by the air pressure to cause the rod and sleeve to close the jet and orifice upon the cessation of said air pressure.
2. In an atomizer of the type set forth, a casing adapted to receive air under pressure, a pipe for conducting liquid mounted in the casing, a nozzle associated with said casing provided with a central orifice for the discharge of the air and liquid, an element slideable along the pipe and 15 movable in a direction away from the nozzle by the air pressure, a jet upon the pipe for the discharge of liquid extending into and in spaced relation to the orifice, a cleaning rod connected to said element and constructed and arranged to be moved thereby in a direction to close said jet, a cleaning sleeve in the path of the element slidably mounted upon the jet, and a resilient means arranged to exert pressure in opposition to the air pressure whereby upon the 20 falling of the air pressure the said means will move the element to cause the rod and sleeve to close the jet and orifice respectively.
3. In an atomizer of the type set forth, a casing adapted to receive air under pressure and 25 including a nozzle provided with a central orifice, a liquid conducting pipe disposed axially of the casing, a jet for the liquid mounted upon the pipe and extending into and in spaced relation to the orifice, an element slideable along the 30 pipe and movable thereon in a direction away from the orifice by air pressure and movable towards the orifice by resilient means, a cleaning member carried by said element slideable in the jet and normally closing the same, and a cleaning member slidably mounted upon the jet 35 in the path of the element and constructed and arranged to enter the space between the orifice of the nozzle and jet.
4. In an atomizer of the type set forth, a casing adapted to receive air under pressure, a pipe 40 for conducting a liquid fixed in the casing axially thereof and provided with diametrically opposed longitudinal slots, an element responsive to air pressure of less diameter than the bore of the pipe extending through the slots and longitudinally movable therein, a nozzle in one end of the casing in alignment with the pipe and provided with an orifice, a jet upon the pipe extending into and in spaced relation to the orifice, a cleaning member fixed to an intermediate portion 45 of the element slideable in the jet and normally closing the jet, a second cleaning member slidably mounted upon the jet normally contacting with the element and closing the portion of the orifice exterior of the jet, a spring surrounding the pipe and engaging the side of the element remote from the nozzle for maintaining the cleaning members in closed position when the air pressure is discontinued, and a compressible 50 housing concentric with the pipe and including an annular base engaging the opposite end of the casing from the orifice, a body surrounding the pipe, and an annular head engaging the second cleaning member.
5. In an atomizer of the type set forth, a casing 55 adapted to receive air under pressure and including a front end and a rear end, a nozzle in the front end of the casing provided with a central orifice for the discharge of the air and liquid, a pipe for conducting liquid fixed in the rear end of the casing, a jet upon the end of the pipe having a stem extending into and in spaced relation to the orifice and provided with an intermediate external shoulder, an element slideable along the pipe and rearwardly movable 60 responsively to the action of air pressure, a spring upon the pipe for advancing the element, a cleaning member upon the element slideable in the jet to close the same, and a cleaning member in the path of the element comprising a skirt slideable upon the body of the jet, an intermediate shoulder engageable with the shoulder upon the jet, a sleeve slideable upon the stem of the jet to close the portion of the orifice between the nozzle and jet, and air pressure means 65 for moving the sleeve away from its closed position.
6. In an atomizer of the type set forth, a casing 70 including a tubular body, a front end plate, a rear end plate, and flanged nuts detachably engaging the plates with the body, each of said plates having a central opening provided with a thread, an inlet in the body for admitting air under pressure, a liquid conducting pipe provided with a thread detachably engaging the thread in the rear end plate, a nozzle provided with a thread detachably engaging the thread in the front end plate and provided with a central orifice to permit the discharge of air and liquid, a jet upon the pipe extending into and in spaced 75 relation to the orifice, an element slideable along the pipe movable in a direction away from the orifice by air pressure, a spring concentric with the pipe for moving the element towards the orifice, a jet cleaning member upon the element slideable in the jet under the influence of the spring to close the jet, a nozzle cleaning member slidably mounted upon the jet normally in contact with the element and constructed and arranged to slide into the portion of the orifice exterior of the jet, a head slidably mounted upon the nozzle cleaning member movable in a direction away from the orifice by air pressure, and a lateral shoulder upon the nozzle cleaning member intermediate the element and the head and in the path of the head.
7. In an atomizer of the type set forth, a casing 80 provided with an air inlet for the admission of air under pressure and including a front end and a rear end, the front end having a central opening provided with a thread, a nozzle in the opening provided with a thread engageable with the first mentioned thread and provided with a central orifice for the discharge of air and liquid, a pipe for conducting liquid supported in the rear end of the casing, a jet upon the end of the pipe extending into the central portion of the orifice, an element slideable along the pipe and rearwardly movable thereon by air pressure, a resilient means upon the pipe adapted to advance the element towards the nozzle, a cleaning member upon the element slideable in the jet to close the jet, a cleaning member in the path of the element slideably mounted upon the jet and constructed and arranged to slide into the 85

- orifice in contact with the jet and nozzle when the element is advanced, and compressible means actuated by the air pressure for moving the cleaning members away from their advanced positions.
8. In an atomizer of the type set forth, a casing provided with an inlet for the admission of air under pressure and including a front and rear end, the front end having a central opening provided with a thread, a nozzle in the opening comprising a body portion and a terminal flange, said body portion being provided with an external thread engageable with the first thread, with a central orifice for the discharge of air and liquid, an annular outwardly tapering rearwardly directed recess extending from the orifice to the end face of the body portion, and with a forwardly directed outwardly flaring cavity extending from the orifice to the flange, a pipe for conducting liquid fixed in the rear end of the casing, a jet upon the end of the pipe extending into the central portion of the orifice, a cleaning member slidably mounted in the jet forwardly movable to close the jet, a cleaning member slidably mounted upon the jet and forwardly movable to close the portion of the orifice exterior of the jet, resilient means for advancing the cleaning members to close the orifice, and air pressure means for moving the cleaning members away from their closed positions.
9. In an atomizer of the type set forth, a casing adapted to receive air under pressure, a nozzle in the casing provided with an orifice for the discharge of air and liquid, a liquid conducting pipe disposed axially of the casing, a jet for the liquid mounted upon the pipe and disposed centrally of the orifice, an element slideable along the pipe and movable towards and away from the orifice, a cleaning member attached to the element and slidably mounted in the jet to enter the orifice when the element is moved towards the orifice, a tubular cleaning member contacting with the element and slidably mounted upon the jet to also enter the orifice when the element is moved towards the orifice, and compressible means actuated by the air for moving the element away from the orifice, and resilient means for moving the element towards the orifice.
10. In an atomizer of the type set forth, a casing adapted to receive air under pressure, a nozzle in the casing provided with an orifice for the discharge of air and liquid, a pipe for conducting liquid mounted in the casing, a jet upon the pipe extending centrally of the orifice, an element slideable along the pipe, a cleaning member upon the element normally closing the jet, a second cleaning member normally contacting with the element and closing the orifice between the jet and the nozzle, a spring engaging the element to maintain the cleaning members in closed positions, and compressible means engaging the element and adapted to engage the second cleaning member and actuated by the air pressure for retracting the spring to open the jet and for withdrawing the second cleaning member from the orifice.
11. In an atomizer of the type set forth, a casing adapted to receive air under pressure, a nozzle in the casing provided with an orifice for the discharge of air and liquid, a pipe for conducting liquid mounted in the casing, a jet upon the pipe extending centrally of the orifice, an element slideable along the pipe, a cleaning member upon the element normally closing the jet,
- a second cleaning member normally contacting with the element and closing the orifice between the jet and the nozzle, a spring engaging the element to maintain the cleaning members in closed positions, and a compressible housing engaging the element and adapted to engage the second cleaning member and actuated by the air pressure for retracting the spring to open the jet and for withdrawing the second cleaning member from the orifice.
12. In an atomizer of the type set forth, a casing provided with an air inlet for the admission of air under pressure and including a front end and a rear end, a nozzle mounted in the front end provided with a central orifice for the discharge of air and liquid, a pipe for conducting liquid fixed in the rear end of the casing, a jet upon the free end of the pipe in the central portion of the orifice, an element slideable along the pipe, a cleaning member attached to the element and slideable in the jet to close the jet, a second cleaning member in the path of the element slideably mounted upon the jet and normally registering in the portion of the orifice around the jet, a spring upon the pipe engaging the element for maintaining the cleaning members in closed position when the air pressure is discontinued, a compressible housing surrounding the pipe, the spring, and the element, including an annular base fixed to the rear end of the casing, a compressible resilient side, an annular head slideably engaging the second cleaning member, a lateral shoulder upon the second cleaning member adjacent the element and in the path of the head and an extension upon the head engaging the front of the element, said housing being adapted to be compressed responsively to the action of the air to withdraw the cleaning members from the orifice.
13. In an atomizer of the type set forth, a casing adapted to receive air under pressure, a pipe for conducting liquid and mounted in the casing, a nozzle associated with said casing provided with a central orifice, a jet connected with the pipe for the discharge of liquid and extending into and in spaced relation to the orifice, a cleaning member normally closing the portion of the orifice exterior of the jet and movable in a direction away from the nozzle, air pressure means for moving the cleaning member away from its closed position, and means for maintaining the cleaning member in closed position when the air pressure is removed.
14. In an atomizer of the type set forth, a casing adapted to receive air under pressure, a pipe for conducting liquid mounted in the casing, a nozzle associated with said casing provided with a central orifice for the discharge of the air and liquid, a jet connected with the pipe for the discharge of liquid and extending into and in spaced relation to the orifice, a cleaning member normally closing the portion of the orifice exterior of the jet and movable in a direction away from the nozzle, air pressure means for moving the cleaning member away from its closed position, and resilient means for urging the cleaning member to closed position.
15. In an atomizer of the type set forth, a casing adapted to receive air under pressure, a nozzle associated with said casing provided with a central orifice for the discharge of air and liquid, a jet for the discharge of liquid mounted in the casing and annularly spaced relatively to the orifice, a cleaning member mounted upon the jet and movable thereon in opposite directions

- for alternately closing and opening the annular space, resilient means for moving said member in one direction, and air pressure means for moving said member in the opposite direction.
- 5 16. In an atomizer of the type set forth, a casing adapted to receive air under pressure, a nozzle associated with said casing provided with a central orifice, a jet for the discharge of liquid mounted in the casing and annularly spaced relative to the orifice, whereby an annular opening is provided about said jet for the discharge of air, and means mounted in said casing and movable into said annular opening to the point of discharge of the jet for cleaning said annular opening.
- 10 17. In an atomizer of the type set forth, a casing adapted to receive air under pressure, a nozzle associated with said casing provided with a central orifice, a jet for the discharge of liquid mounted in the casing and annularly spaced relative to the orifice, whereby an annular opening is provided about said jet for the discharge of air, and cleaning means mounted in said casing and normally closing said annular opening and movable away from said opening in response to pressure of the air during operation of the atomizer.
- 15 18. In an atomizer of the type set forth, a casing adapted to receive air under pressure, a nozzle associated with said casing provided with a central orifice, a jet for the discharge of liquid mounted in the casing, extending throughout the length of the orifice, and annularly spaced relative to the orifice, whereby an annular opening is provided about said jet for the discharge of air, and means mounted in said casing and movable lengthwise throughout the length of the jet and of said annular opening for cleaning said annular opening.
- 20 19. In an atomizer of the type set forth, a casing adapted to receive air under pressure, a nozzle associated with said casing provided with a central orifice, a jet for the discharge of liquid mounted in the casing and annularly spaced relative to the orifice, whereby an annular opening is provided about said jet for the discharge of air, and means mounted in the casing slidably relative to the orifice, whereby an annular opening is provided about said jet for the discharge of air, and means mounted in the casing slidably engaging both the jet for the liquid and the nozzle and movable into and out of said annular opening for cleaning said annular opening.
- 25 20. In an atomizer of the type set forth including a front end and a rear end, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.

WALTER MACDONALD. 40

DISCLAIMER

2,097,696.—*Walter Macdonald, North Providence, R. I. SELF CLEANING ATOMIZER.*
 Patent dated November 2, 1937. Disclaimer filed June 28, 1939, by the inventor; the assignee, *American Moistening Company*, agreeing and consenting.

Hereby enters this disclaimer to claims 13, 14, 16, and 17 of said Letters Patent.
 [Official Gazette July 25, 1939.]

- for alternately closing and opening the annular space, resilient means for moving said member in one direction, and air pressure means for moving said member in the opposite direction.
- 5 16. In an atomizer of the type set forth, a casing adapted to receive air under pressure, a nozzle associated with said casing provided with a central orifice, a jet for the discharge of liquid mounted in the casing and annularly spaced relative to the orifice, whereby an annular opening is provided about said jet for the discharge of air, and means mounted in said casing and movable into said annular opening to the point of discharge of the jet for cleaning said annular opening.
- 10 17. In an atomizer of the type set forth, a casing adapted to receive air under pressure, a nozzle associated with said casing provided with a central orifice, a jet for the discharge of liquid mounted in the casing and annularly spaced relative to the orifice, whereby an annular opening is provided about said jet for the discharge of air, and cleaning means mounted in said casing and normally closing said annular opening and movable away from said opening in response to pressure of the air during operation of the atomizer.
- 15 18. In an atomizer of the type set forth, a casing adapted to receive air under pressure, a nozzle associated with said casing provided with a central orifice, a jet for the discharge of liquid mounted in the casing, extending throughout the length of the orifice, and annularly spaced relative to the orifice, whereby an annular opening is provided about said jet for the discharge of air, and means mounted in said casing and movable lengthwise throughout the length of the jet and of said annular opening for cleaning said annular opening.
- 20 19. In an atomizer of the type set forth, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.
- 25 20. In an atomizer of the type set forth including a front end and a rear end, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.
- 30 21. In an atomizer of the type set forth, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.
- 35 22. In an atomizer of the type set forth, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.
- 40 23. In an atomizer of the type set forth, a casing adapted to receive air under pressure, a pipe for conducting a liquid fixed in the casing axially thereof and provided with longitudinal slots, a nozzle in the front end of the casing provided with an orifice, an element of less diameter than the bore of the pipe extending loosely through the slots and longitudinally movable therein by air pressure in a direction away from the nozzle, resilient means upon the pipe adapted to advance the element towards the nozzle, a tubular jet fixed to the pipe provided with a tapering internal shoulder intermediate its length and extending into and in spaced relation to the orifice, a cleaning member slidable in the jet to close the same fixed to said element and provided with a tapering shoulder adapted to register with the first shoulder, a second cleaning member slidably mounted upon the jet in the path of the element and normally closing the space formed in the orifice, air pressure means for moving the second cleaning member in a direction away from the orifice, and a housing surrounding the pipe including an annular base secured to the rear end of the casing, a compressible body secured to the base, and a head slidably engaging the second cleaning member.

WALTER MACDONALD. 40

DISCLAIMER

2,097,696.—*Walter Macdonald*, North Providence, R. I. SELF CLEANING ATOMIZER. Patent dated November 2, 1937. Disclaimer filed June 28, 1939, by the inventor; the assignee, *American Moistening Company*, agreeing and consenting.

Hereby enters this disclaimer to claims 13, 14, 16, and 17 of said Letters Patent.
